CLOSET BOWL CONSTRUCTION

Charles R. Winstanley, Johnstown, Pa.

Application December 10, 1931
Serial No. 580,205

2 Claims. (Cl. 4—257)

This invention relates to closet bowl construction, the primary object of the invention being to provide a bowl wherein ready access to the passageways thereof may be had, to the end that 5 obstructions which may find their way into the passageways to clog the bowl, may be readily and easily removed, eliminating the necessity of disconnecting the bowl from its fixtures.

An important object of the invention is the 10 provision of a bowl having an opening in one of the partitions formed by the passageways, in which a removable plug is positioned, the construction of the plug being such as to present a smooth upper surface.

15 A still further object of the invention is to provide a plug which may be readily released with the usual screw driver, without the necessity of employing special tools for this purpose.

With the foregoing and other objects in view, 20 which will appear as the description proceeds, the invention resides in the combination and arrangement of parts and in the details of construction hereinafter described and claimed, it being understood that changes in the precise embodiment of the invention herein disclosed, may be made within the scope of what is claimed, 25 without departing from the spirit of the invention.

Referring to the drawing:

30 Figure 1 is a vertical sectional view through a closet bowl constructed in accordance with the invention.

Figure 2 is a bottom plan view of the plug.

35 Figure 3 is a fragmental sectional view through the plug and bowl, showing the plug as secured in position.

Referring to the drawing in detail, the reference character 5 designates a closet bowl of the 40 usual construction, the same being provided with passageways 6 defining an upper partition 7 and a lower partition 8, the upper partition 7 being formed with a circular opening to receive the plug 9.

The opening is formed with a shoulder 10 45 that provides a rest for the plug 9, to prevent the plug from being extended into the opening of the partition, too far.

As clearly shown by Figure 2 of the drawing, 50 the bottom surface of the plug is formed with cut away portions 10' to accommodate the pivoted securing members 11, which are formed with fingers 12 that fit into slots 13 formed in the wall of the opening.

55 Stops 14 are formed on the members 11, and are adapted to engage the shoulders 15, to re-

strict movement of the members 11 in one direction. These members 11 are secured to the pins 16 that extend through the plug proper, the pins 16 being formed with heads 17 that have notches 18 to receive a screw driver, so that by inserting 60 a screw driver into the notch of a pin 16, the member with which the pin is connected may be rotated to cause the member 11 to disengage the wall of the opening, to the end that the plug may be readily removed so that access to the 65 passageways of the bowl may be readily had.

The plug of course may be replaced by merely positioning the plug in the opening, and rotating the pins, to move the members 11 to their securing positions.

Having thus described the invention what is claimed is.

I claim:

1. A bowl of the class described comprising a body portion, a partition forming a part of the 75 body portion and dividing the body portion into compartments, said partition having an opening, the wall of the opening having slots, a plug fitted within the opening, and pivoted securing members on the plug and adapted to swing into 80 the slots locking the plug within the opening.

2. A bowl of the class described comprising a body portion, a partition within the body portion, said partition having an opening, the wall of the opening having slots, a plug fitted within 85 the opening, pivoted securing members positioned on the bottom of the plug, pins extending through the plug and connected with the securing members to move the securing members when the pins are rotated, and said pins having 90 heads for the reception of a tool to rotate the pins and securing members to move the securing members into and out of the slots.

CHARLES R. WINSTANLEY.
